INTERCHANGEABLE DISPLAY

Sidney H. Sonn, New York, N. Y.

Application August 31, 1940, Serial No. 355,066

4 Claims. (Cl. 40—125)

This invention relates generally to display units. It is an object of the present invention to provide a display unit having a readily removable and reversible panel or layer with characteristically or distinctively different surfaces or faces, whereby either face may be placed into view at will.

It is another object of the present invention to provide a display unit having a plurality of removable and reversible layers, each layer carrying distinctively different faces, whereby there may be presented to view on the display unit layers having different colors, textures or the like, or the same color, texture or the like, as desired.

It is a further object of the present invention to provide a display unit in which the exposed layers may be readily removed and reversed or replaced by other layers having other different colors or other characteristically different faces, and whereby aesthetic combinations of surfaces may be presented to the eye of the observer.

Yet another object of the present invention is in the provision of means in the display unit whereby the said top layers may be efficaciously removed, positioned and maintained on the unit.

The invention in one of its aspects comprises a display unit in the form of a body having a top member and a wall member angularly disposed relatively to the top member, an edge of the top member being adjacent an edge of the wall member. Disposed at the adjacent edges of the top and wall members is a retainer having a portion spaced from and extending over the top member and another portion spaced from and extending over the wall member. Over the top member is disposed a preferably removable and reversible layer and over the wall member is disposed a removable and reversible flexible layer, both layers respectively having their adjacent edge portions interposed between their respective members and said retainer. Both the layers or either of them have distinctively different faces or surfaces, distinctive as to color, texture, coating, etc.

The above and other objects of the invention and the means for their attainment will be more apparent from the following detailed description, taken in connection with the accompanying drawing, illustrating a certain embodiment of which the invention may be realized and in which:

Fig. 1 is a top view of a display unit made in accordance with the invention;

Fig. 2 is a front view thereof;

Fig. 3 is a back view thereof;

Fig. 4 is a section taken along 4—4 of Fig. 1; and

Fig. 5 is a detail sectional view of a portion of a reversible layer embodied in the invention.

Referring now more particularly to the drawing there is disclosed a display unit having a body 10, which may be made of any suitable material. The example in the drawing shows the body 10 as being hollow and comprising a frame structure generally indicated by the numeral 11 and a front wall member 12. The frame structure 11 is formed by a bottom member 13 having an arcuate edge 13a, uprights 14a, 14b, 14c secured to bottom member 13 and a top member 15 secured to these uprights. The top member 15 also has an arcuate edge 15a. The front wall member 12 is arcuately-shaped conforming generally to the arcuate-edge contours of the top and bottom members 15, 13 and is secured to the uprights 14a, 14b, 14c by any suitable means. The frame structure 11 is preferably made of wood, although any other suitable material may be employed, particularly the top and bottom members 15, 13 which may be made of light metal, fibreboard, pasteboard or composition material. The arcuate front wall member 12 is preferably made of flexible pasteboard for economy, but, again, any other suitable material may be employed, such as, the materials heretofore mentioned, with respect to the top and bottom members 15, 13.

It is preferable that either the front wall member 12 or the top member 15 extend beyond the other at the top of the display unit to provide a ledge or extension at which may be disposed a retainer 16. As shown in the drawing this retainer 16 may be in the form of an arcuately shaped corner element secured to the extension 17 of front wall member 12 adjacent the arcuate edge 15a of top member 15. Corner element 16 has a flange portion 18 spaced from and extending over and above top member 15 and another flange portion 19 spaced from and extending over front wall member 12. The retainer 16 is fixed in position by any suitable means, such as, for example, the nails 20 which project through extension 17 and into the uprights 14a, 14b, 14c.

Positioned on the top member 15 and substantially co-extensive therewith is a preferably removable and reversible plate or layer 21 having its front arcuate edge portion accommodated or set in the space between the top member 15 and flange portion 18 of retainer 16; and positioned on the front wall member 12 and substantially co-extensive therewith is a removable and reversible flexible layer 22 conforming in shape to front wall member 12 and having its upper edge portion accommodated or set in the space between front

wall member 12 and flange portion 19 of retainer 16.

The layers or plates 21, 22 may be made of any suitable material, but it is preferable for economy to make the same of pasteboard. Fig. 5 illustrates in section a portion of either one of the plates 21, 22. The body portion 23 is made preferably from cardboard. Its surfaces or faces 24, 25 are distinctively or characteristically different from each other, either in color, design, texture or material. For example, different colors and/or designs may be printed on the faces 24, 25 of the body portion 23; or the faces 24, 25 may be layers of fabric, paper or other cellulosic or resinous material carrying appropriately different colors; designs or configurations; and having any desired texture or quality.

By providing the removable panels or plates 21, 22 with surfaces or faces distinctively or characteristically different from each other as aforesaid, various attractive, effective and aesthetic combinations may be produced.

By providing the retainer 16, either or both of the layers 21 and 22 may be readily reversed or replaced by other panels having other colors and other characteristics.

It is preferable that the front plate or layer 22 be provided with hinged flange portions 30, 31 which may be secured to the uprights 14a and 14b, respectively, by any suitable means, such as, the tacks 32. The corner member 16 not only functions as a retainer for the layers 21, 22, but also as an embellishment for the display unit.

Although the drawing discloses a semi-cylindrically shaped display unit, it is understood that the display unit contemplated by this invention may assume any shape or size and may be utilized as a display platform or display blocks or both, whereby articles may be supported thereby or a plurality of units arranged adjacent or over each other as an embellishment for display purposes.

Furthermore, although there has been disclosed in the drawing and described in the specification one of the modes in which it is contemplated embodying the invention, it is desired that the invention in no way be limited to the details of such disclosure, for in the further practical application of the invention, changes in the forms and proportions may be made as circumstances require or experience suggests without departing from the spirit of the invention within the scope of the appended claims.

Having thus described the invention what is claimed as new and what is desired to be secured by Letters Patent is:

1. A display unit comprising a hollow body having a top member and a front wall member adjacent said top member, one of said members having a portion extending beyond the other of said members, an element disposed over said extended portion of said one of said members and having flanges respectively spaced from and extending over said members, a removable layer over said top member and substantially co-extensive therewith, a portion of said layer interposed between said top member and the flange of said element extending thereover, another removable layer over said wall member and sub-

stantially co-extensive therewith, a portion of said another layer interposed between said wall member and the flange of said element extending thereover, said another layer having hinged lateral flaps secured to said body, each of said layers having distinctively different surfaces.

2. A display unit comprising a hollow body having a top member and a wall member angularly disposed relatively to said top member, an edge of said top member being adjacent an edge of said wall member, one of said members having a portion extending beyond the other of said members at said adjacent edges, an element disposed over said extended portion of said one of said members and having flanges respectively spaced from and extending over said members, a removable layer over said top member and substantially co-extensive therewith, a portion of said layer interposed between said top member and the flange of said element extending thereover, another removable layer over said wall member and substantially co-extensive therewith, a portion of said another layer interposed between said wall member and the flange of said element extending thereover, said another layer having hinged lateral flaps secured to said body, each of said layers having distinctively different surfaces.

3. A display unit comprising a hollow body having a top member provided with an arcuate edge and a front arcuately-shaped wall member angularly disposed relatively to said top member, said arcuate edge of said top member being adjacent an edge of said wall member, one of said members having a portion extending beyond the other of said members at said adjacent edges, an element disposed over said extended portion of said one of said members and having flanges respectively spaced from and extending over said members, a removable and reversible layer over said top member and substantially coextensive therewith, a portion of said layer interposed between said top member and the flange of said element extending thereover, a removable and reversible flexible layer over said wall member and substantially coextensive therewith, a portion of said flexible layer interposed between said wall member and the flange of said element extending thereover, each of said layers having distinctively different surfaces.

4. A display unit comprising a body having a top member and a wall member angularly disposed relatively to said top member, an edge of said top member being adjacent an edge of said wall member, an element disposed over said adjacent edges and having flanges respectively spaced from and extending over said members, a removable and reversible layer over said top member and substantially coextensive therewith, a portion of said layer interposed between said top member and the flange of said element extending thereover, a removable and reversible flexible layer over said wall member and substantially coextensive therewith, a portion of said flexible layer interposed between said wall member and the flange of said element extending thereover, each of said layers having distinctively different surfaces.
